UNITED STATES PATENT OFFICE.

SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,295,405.

Specification of Letters Patent. Patented Feb. 25, 1919.

Application filed March 3, 1917. Serial No. 152,230.

To all whom it may concern:

Be it known that I, SAMUEL B. WILLIAMS, Jr., a citizen of the United States, residing at Brooklyn, in the county of Kings and State of New York, have invented certain new and useful Improvements in Telephone-Exchange Systems, of which the following is a full, clear, concise, and exact description.

10 This invention relates to a telephone exchange system in which the calling line is extended to an operator's position, and in which means identified with such calling line is automatically operated for the purpose of causing the indication before the operator of the number of the calling line and also the charging of the call to such calling line if a connection is successfully established.

20 In accordance with a feature of the invention, a device in the nature of an automatic switch is associated with each line and is operated after a calling line is extended to an operator's position to associate an interrupting device, common to a large number of lines, with a conductor leading to such operator's position, which interrupting device is arranged to send impulses over said conductor in accordance 25 with the designation of the calling line, such impulses being utilized to actuate suitably arranged apparatus for the purpose of indicating the number of the calling line.

In accordance with a further feature of the invention the same apparatus identified with the line may be subsequently employed, providing a call has been successfully extended to the called line, to operate apparatus to charge the call to the calling line. This call charging apparatus may be individual to a cord circuit at an operator's position, and may be automatically operated to print or otherwise mark upon a record strip ticket the number of the calling line to which the call is to be charged.

Other features of the invention not specifically referred to above will more clearly appear from the annexed specification and from the drawings, in which—

50 Figure 1 represents diagrammatically the apparatus and circuits associated with the calling line; and

Figs. 2 and 3 represent the circuits and apparatus associated with the cord circuit in the operator's position, the complete sys-

tem being shown with Fig. 2 at the right of Fig. 1, and Fig. 3 below Fig. 2.

The invention is shown as applied to a system such as is disclosed in the applicant's previously filed application, Serial No. 107,990, filed July 1, 1916.

However, for the sake of simplicity, only so much of the circuits of the previously filed application are disclosed herein as is necessary for the complete understanding of the present invention. Those parts of the circuits of the former application which are omitted, and their relation to the present invention, may be understood by referring to such previously filed application, 70 Serial No. 107,090 the same reference numerals being utilized as far as possible to designate similar parts of the system disclosed in the previously filed application and the system disclosed in this application. 75

Referring to Fig. 1 of the drawing, there is provided individual to each line, a switch such as indicated at 1. These switches are provided with a rotatable arm 2, which is adapted to be moved over stationary terminals indicated at 4, 5, 6, 7 and 13, by means of the intermittent energization and deenergization of a stepping magnet 3, the pawl operated by the armature of the magnet 3 being arranged to step the arm 2 forward upon the release of such magnet. Normally the arm 2 is in contact with the first stationary terminal 4, and there are as many stationary terminals as there are digits in the maximum line number in the system. For purposes of illustration, it is assumed that the number of the line shown and indicated as A' is 15732. There is provided common to the exchange an interrupting device indicated as a whole at 8. This interrupting device comprises a shaft 9, adapted to be driven in a counter clockwise direction from some suitable source of power (not shown), upon which are mounted a series of commutator disks. The No. 0 commutator is provided with one short conduct-

commutator is provided with one short insulated segment, followed by a long insulated segment, the No. 1 commutator with two short conducting segments, the No. 2 with three, the No. 3 with four, etc. The stationary terminals of the switch individual to any line are connected to brushes making contact with the particular commutators which represent the number of such 110

line. Therefore, in the case of the line A', the first terminal 4 is connected to the No. 1 commutator, the second terminal 5 to the No. 5 commutator, the third terminal 6 to the No. 7 commutator, the fourth terminal 7 to the No. 3 commutator, and the fifth terminal 13 to the No. 2 commutator. Similarly, the other switch 1, which, it is assumed, is associated with line 3682, has 10 stationary terminals which are connected to the Nos. 0, 3, 6, 8 and 2 commutators respectively. When a suitable control circuit is established to the call indicating device, as will more clearly appear hereinafter, a series of quick interruptions takes place in the control circuit including the magnet 3, from the commutator which is associated with the stationary switch terminal with which the brush 2 happens to be 15 in contact. These interruptions being short will not affect the slow release magnet 3, which will remain energized after all the interruptions of the series individual to the particular terminal with which the 20 arm 2 is in contact have terminated and will release when the circuit is opened for a long period by the long insulated segment on the commutator moving the arm 2 to the next stationary terminal where the 25 same process will be repeated until all the terminals have been traversed. In order to avoid restoring the switch after each set of impulses, the switch may be arranged to travel always in the same direction, and in 30 case of a five-digit system, each fifth terminal thereof may be connected in multiple. The indicating device may be of any well-known type in which a series of movable indicator arms or wheels are stepped to an 35 indicating position in response to series of short impulses and in which a slow operating magnet is utilized to shift the impulse sending device from one indicating arm or disk to another. One suitable form of indicating device is disclosed in Fig. 3. This 40 consists of a shaft 310 which may be rotated through a pawl and ratchet mechanism by the quick acting magnet 305 and which may be elevated through a similar mechanism by 45 the release of the slow-release magnet 304. A set of arms or brushes 311, 312, 317, 319 and 321 loosely mounted on said shaft are 50 adapted to travel over rows of contacts of which there are ten in each row. Associated 55 with each contact is a lamp, the number 9 lamp of each row being indicated at 335. The arrangement is such that when a brush is moved to a particular contact a circuit for the lamp individual to such contact is partially 60 established, which circuit is completed when all of the arms are set, through the contact 324 operated in the topmost position of the shaft 310. A yoke indicated at 336 is secured to the shaft 310 and carries a pawl 65 337, which in the lowermost portion of the

shaft 310 engages a ratchet on the arm 321, and as the shaft is rotated rotates such arm. In successive vertical positions of the shaft 310 the pawl 337 engages the arms 319, 317, 312 and 311. After an arm has been operated 70 through the rotation of the shaft 310 it is held by a locking pawl such as 313, 316, 318 75 320 and 322. A pawl 338 controlled by the armature of the vertical stepping magnet 304 holds the shaft 310 in its rotated position until the shaft is stepped vertically, when such pawl is operated and permits the shaft 310 to be rotated back to normal under the influence of a suitable spring not shown. The holding magnet 315 is energized before 80 the indicator is set and is released when the indicator has performed its function. The release of this magnet withdraws the locking pawls 314, 318, 316, 318, 320 and 322 and restores all parts of the indicator to normal. 85 The particular combination of lamps illuminated in any given case indicates to the operator the number of the calling line.

The call charging device may be of any suitable type in which mechanisms operate 90 to make a record either by printing or otherwise marking a suitable record strip or card for the purpose of identifying the calling line in response to a series of sets of impulses indicating the number of such called line. 95 The call charging device shown on Fig. 3 is merely a diagrammatic representation in which the magnet 329 is a quick acting magnet which responds to each impulse of a set, and the magnet 330 is a slow-release magnet 100 which releases upon the termination of a set of impulses. The magnet 329 as shown operates the magnet 352 which through an escapement mechanism serves to position a type wheel carrying numbers, and the slow 105 operating magnet 330 when released closes at its back contact a circuit for the magnet 350, which serves to bring the type wheel which has thus been positioned into contact with the record strip for the purpose of making a 110 record of the number represented by the set position of the type wheel. The magnet 330 may be also utilized, as indicated, to operate or move the arm 332 one step for each set of impulses, which arm may be utilized at the 115 end of the entire set of series of such impulses to close a circuit for the purpose of restoring the entire apparatus to normal.

The relay 328 which is operated upon the completion of the entire train of impulses 120 may be utilized to cause the severing of a strip thus perforated or printed and the card thus formed may be sorted by machinery for the purpose of determining at the end of a given period the number of tickets which 125 represent calls on a given calling line. The relay 328 when operated causes the operation of magnet 351, which operates the knife 354 to sever the record strip.

The invention will best be understood by 130

5 a description of the operation in extending the calling line to an operator's position and indicating the number of the calling line thereat, and also operating the message register to charge for the call in case the call is successful. The call may be for example initiated by the subscriber A', who removes his receiver from the hook, thus energizing the line relay 12. The line relay 12 establishes a 10 circuit for the cord relay 19, which, in turn, controls the relay 24 and the sequence switch 100 in identically the same manner as the corresponding relay and sequence switch are controlled in application, Serial No. 107,090.

15 It will be assumed, therefore, that a line 15 finder, the brushes of which are illustrated at 14, 15, 16 and 17 and terminals individual to the calling line at 20, 21, 22 and 23, and a cord finder the brushes of which are indicated at 25, 26, 27 and 28 and terminals individual to an idle cord at 29, 30, 31 and 32, have been operated identically as in such application to connect the calling line A' to the cord shown in Fig. 2.

20 As soon as the brushes 25 to 28 are brought into contact with the terminals 29 to 32 a circuit is established for the energization of relays 151, 154 and 157 of the cord circuit. This circuit may be traced from 25 battery through the windings of relays 151, 154 and 157 in parallel (the branch through the winding of the relay 157 passing through contacts 509 (position 1) of the calling cord sequence switch 500) to sequence switch contact 505 (position 1) and from thence by 30 way of the listening key sequence switch contact 405 (position 1), left-hand contact and armature of the relay 152, conductor 87, contact 31, brushes 27 and 16, terminal 21, winding of cut-off relay 11. Therefore, the 35 instant that the connecting circuit has been appropriated, the three relays 151, 154 and 157 of the cord circuit are operated. Relay 154, in operating, closes at its left armature 40 and front contact a locking circuit for all three of these relays, which circuit extends by way of sequence switch contact 506 (position 1), sequence switch contact 406 (positions 1 to 6) to ground. The three relays 45 are thus held locked up while the listening key sequence switch is moved from its normal position 1 to its listening position 7. This movement of the listening key sequence switch is effected by a circuit which extends 50 from battery through a motormagnet and contact 403 (position 1) of the sequence switch 400, contact 507 (position 1), and right-hand front contact and armature of relay 154 to ground.

55 In leaving position 1, the listening key sequence switch for the group breaks at contact 405 (position 1) the connection of the sleeve conductor 87 and battery by way of the windings of relays 151, 154 and 157, but 60 relay 151, in operating, has in the mean-

while completed a circuit which extends from battery, through the winding of relay 152, front contact and armature of relay 151 to ground. As a result, relay 152 is energized, and at its left-hand armature and 70 front contact has disconnected the conductor 87 from the branch extending by way of the sequence switch contact 405 (position 1) and has connected it instead with battery by way of the left-hand armature and front 75 contact of relay 152 and the winding of relay 155. The relay 155 thereupon operates to close the circuit of the talking conductor 86, which is normally maintained open.

80 After relay 152 is initially energized by the operation of relay 151, it is maintained operated by a path to ground, which is closed at contact 407 as soon as the sequence switch 400 reaches position 2, and which is maintained closed until the sequence switch 85 moves out of position 7. Relay 157, operating, connects the operator's telephone set with the talking conductors 85 and 86, extending to the telephone set of the calling subscriber. The operator's telephone set, 90 which is not shown, is connected to the leads indicated in Fig. 2 at *a* and *b*, and from thence by way of contacts 512 and 513 (position 1) through the armatures and contact of relay 157, contacts 510 and 511 (position 1) to the conductors 85 and 86.

95 The circuit between the operator's telephone and the telephone of the calling subscriber is thus completed. At the same instant as previously described the relay 154 100 operates to close the circuit for moving the sequence switch 400 out of position 1, which sequence switch continues to move until it reaches position 7. Just before the sequence switch reaches position 7, however, the previously traced circuit for the operator's telephone is opened, due to the fact that the relays 157, 151 and 154 are released when the contact 406 is open on leaving position 6. The operator's telephone set, however, may 105 be maintained in communication with that of the calling subscriber by means of an alternative circuit (not shown), which is in all respects similar to the alternative circuit shown in application Serial No. 107,090. 110 In position 7 of the sequence switch 400, while the operator is ascertaining the number of the called line from the calling subscriber, the indicating apparatus for the purpose of indicating the number of the calling line may be set in operation.

115 The common interrupting device indicated at 8 in Fig. 1 is provided with an extra commutator indicated at 33, which may be termed the pick-up commutator. This commutator is arranged to close a circuit to ground through the relay 300, at a time when the brushes resting on all of the other commutators are inactive, that is, when they 120 are resting upon an insulated portion of such 125 130

commutators. As will presently appear, the purpose of the relay 300 is to associate the indicating device with the switch 1, individual to the calling line, so that this association can take place only when the commutator associated with the first terminal 4 of such switch is in inactive position, and thus mutilation of the series of impulses or interruptions is prevented. The relay 300, therefore, is energized over a circuit which extends from battery through the relay 300, right-hand normal contact of such relay, conductor 301, contact 415 (position 7), conductor 302, and through the pick-up commutator 33 to ground. The relay 300 at its right-hand armature and contact closes a locking circuit for itself which extends over the conductor 303 to the contact 407 (position 7) to ground. At its left-hand armature and contact, the relay 300 places the slow-operating vertical magnet 304 and the quick-operating rotary magnet 305 of the indicating device in series with the slow-release magnet 3 of the switch individual to the line over a circuit which extends from battery, through the magnet 305, magnet 304, normal contact 306 of the indicator, left-hand armature and contact of the relay 300, conductor 307, contact 404 (position 7), left-hand normal contact of the relay 156, conductor 88, cord finder terminal 32, and brush 28, line finder brush 17 and terminal 20, magnet 3, arm 2, terminal 4, through the No. 1 commutator, shaft 9 to ground. As the terminal 4, in the case of the number assumed, is connected to the No. 1 commutator, this circuit will be interrupted twice in quick succession, causing the rotary magnet 305 to be deenergized and energized twice and maintaining the magnets 3 and 304 energized. The two deenergizations of the magnet 305 will cause the pawl 308 to engage the ratchet wheel 309, stepping the shaft 310 through two steps. The shaft 310, in its lowermost position, will step the contact arm 321 into contact with the second terminal, and at the end of the series of two impulses, the magnets 304 and 3 will release. The first of such magnets, through its armature and pawls carried thereby, will step the shaft 310 one step upward, will bring the arm 319 into operative relation with the shaft 310, and will permit the shaft 310 to rotate back to normal. The arm 321 is held in its advanced position by means of the pawl 322, which pawl is moved into engagement with the ratchet carried by arm 321, as are also the corresponding locking pawls of the other arms and the vertical locking pawl 314, due to the energization of the holding magnet 315, which magnet is energized as soon as the sequence switch 400 reaches position 7 over a circuit which extends from battery, through the magnet 315, conductor 303, contact 407 (position 7).

When the interrupter shaft has made a complete revolution, due to the release of the magnet 3, the arm 2 will have been moved into contact with the terminal 5, and the No. 5 commutator will come into operation 70 and will result in six interruptions of the circuit which includes the magnets 3, 304 and 305. Magnets 3 and 304 are energized and held energized during the entire series of interruptions, and the magnet 305 is energized and deenergized for each interruption, stepping the shaft 310 through six steps, and consequently moving the arm 319, which is now associated with the shaft 310, over to the sixth contact, in which position the arm 80 is held by the holding pawl 320. At the termination of this series of impulses, the magnet 304 is released, as well as the magnet 3, and the pawl carried by the armature of the magnet 304 steps the shaft 310 up another step, and brings the arm 317 into operative relation with the shaft 310. The release of the magnet 3 moves the arm 2 into association with the terminal 6, so that when the shaft 9 has made another complete revolution, the No. 7 commutator places impulses 85 on the circuit including the magnets 3, 304 and 305 as before. After eight energizations of the magnet 305, which causes the arm 317 to be stepped to the eighth contact 90 of the row with which it is associated, magnets 3 and 304 are released, magnet 304 stepping the shaft 310 up another step, and magnet 3 stepping the arm 2 into association 95 with the terminal 7. The arm 317 is held in 100 the position to which it was set by the pawl 318, and the arm 312 is associated with the shaft 310. As soon as the shaft 9 has made another revolution, the No. 3 commutator is associated with the No. 7 terminal, and four 105 impulses are sent through the magnets 3, 304 and 305. As a result, the arm 312 is moved over to the fourth contact of the row to which it is individual, being held in such position by the pawl 316, and the shaft 310 110 is stepped up another step, placing the arm 311 in association with such shaft. At the same time, the arm 2 is moved into association with the terminal 13, and after another revolution of the shaft 9, the No. 2 commutator 115 sends three impulses to the magnets 3, 304 and 305, setting the arm 311 into contact with the third contact of the row to which it is associated, in which position it is held by means of the pawl 313. It will be 120 observed that by a counter clockwise rotation of the interrupter 8, the last one of the series of short conducting segments of each of the several commutator disks passes under its co-operating brush at the same instant in the cycle of rotation of the interrupter. By this means the open period of the circuit for slow-to-release magnets 3 and 304 commences at the same point in the rotation of the interrupter for all commutator 125 130

disks, and the long insulating segment following the last conducting segment being sufficiently long to permit the slow magnets 3 and 304 to release and operate the switch 5 1 and the indicating switch, the transition from one digit to the next will occur without mutilation of impulses, whether such transition be from a lesser to a greater numbered digit or vice versa. The shaft 310, due to 10 the release of the magnet 304, is stepped up still another step, and the upper end of such shaft, indicated at 323, engages the contacts 306 and 324, opening the lower contact of 306, and closing the upper contact of 306 15 and of 324. The circuit of the magnets 3, 304 and 305 is interrupted at the contact 306, so that when the brush 2 is moved into association with the next terminal, due to the deenergization of the magnet 3, no impulses 20 will be sent in to the indicating device. The contact 324 connects ground to the shaft 310, and from thence to the arms 321, 319, 317, 312 and 311, causing the illumination of the lamps individual to the second, sixth, eighth, 25 fourth and third contacts of the respective rows, which lamps are illuminated, and indicate to the operator that the number of the calling line is 15732. The indicator will stop in said position, and the lamps will 30 continue to be illuminated until the sequence switch 400 leaves position 7, when the relay 315 is deenergized, and withdraws the various holding pawls, and permits the indicator to restore to normal.

35 The setting of the indicator which has just been described, and which takes place in position 7 of sequence switch 400, takes place during the period employed by the operator in ascertaining from the calling subscriber 40 the number of the called line, testing such called line, and finally establishing connection with such called line, if not busy. The operator, having ascertained the number of the called line, tests by inserting the plug 45 indicated at 170 into the jack 114, which will be assumed to be the calling jack of the called line. When the tip of the plug contacts with the sleeve of the jack, the test takes place. If the line is busy, battery 50 will be found upon such sleeve and a circuit will be extended by way of back contact and right armature of the relay 175 to a test relay at the operator's position (not shown), the operation of which will notify 55 the operator that the particular line is busy. Assuming, however, that the line is idle, the operator inserts the plug 170 in the jack 114, and establishes a circuit for the relays 119, 175, and the cut-off relay 11 of the line in 60 series. This circuit extends from battery to relay 119, relay 175, sleeve of the plug, sleeve of the jack, cut-off relay 11 to ground. The relay 175 closes a circuit that extends 65 from battery to the motormagnet and contact 503 (position 1) of the sequence switch

500, contact 413 (position 7), left-hand front contact of the armature of the relay 175, normally closed contacts of the charge key 176 to ground, thus driving the sequence switch 500 into position 2. In position 2 70 of the sequence switch 500, a circuit is completed from battery, through the motormagnet and contact 403 (position 7) of the sequence switch 400, contact 515 (position 2), back contact and right armature of the relay 154 to ground. The sequence switch 400 is driven out of position 7 into position 15 over this circuit, and a circuit is completed which extends from battery, through the motormagnet of sequence switch 500, 80 contact 504 (position 2), contact 413 (position 8), left-hand front contact and armature of the relay 175, and normal contact of the charge key 176 to ground, whereupon the sequence switch 500 moves into position 85 3. After the sequence switch 500 is moved out of position 2 by movement of the sequence switch 400 out of position 7, as described above, it moves through its various stages until it reaches position 12. The intermediate positions between 2 and 12 may be used to control selective ringing operations, which form no part of the present invention, and which will not be described in detail. From position 12, sequence switch 90 500 moves into position 13, in which position a suitable source of ringing current is connected to the called line for the purpose of signaling, and from position 13, the sequence switch, provided the called subscriber 95 responds, is moved into position 17, which is the through or talking position. The detailed operation of the sequence switch will not be described, as it is sufficient for the purpose of the present invention to assume that the called subscriber 100 has responded, that the sequence switch 500 has reached the through or talking position 17, and therefore that the connection is successfully established. The operator ascertains from the usual supervisory signal that the call has been successfully completed, and then operates the charge key indicated at 176 for the purpose of charging the call to 110 the calling line. The operation of this key, provided the call has been successfully established, and hence the sequence switch 500 is in position 17, establishes a circuit for the relay 156, which circuit may be traced from battery through the relay 156, contact 509 115 120 (position 17), key 176 to ground. The relay 156, at its left-hand armature, establishes a circuit extending from the identifying switch of the calling line to the call-recording device, which circuit, however, is normally open at the back contact and left armature of the relay 325. However, the operation of the charge key 176 also establishes a circuit for the start relay 326 of 125 the call-charging device, which circuit ex- 130

tends from battery, through the relay 326, conductor 327, and the contact and charge key 176 to ground. The relay 326, at its left-hand armature, establishes a locking circuit for itself, which extends from battery, relay 326, left-contact and armature thereof, back contact and right-hand armature of relay 328, back contact of relay 339 to ground. At its right-hand armature, the relay 326 connects the relay 325 into operative relation with the pick-up interrupter which operates, as in the case of the indicator device, to establish a circuit for the relay 325, which circuit extends from battery, relay 325, normal contact of such relay, right-hand armature and contact of relay 326, conductor 302, pick-up commutator 33 to ground. The relay 325, when energized over this circuit, places the magnets 3, 329 and 330 in series with the No. 1 commutator, over a circuit which extends from battery, left-hand armature and back-contact of the relay 328, magnets 330 and 329, left armature and contact of the relay 325, conductor 331, left-hand armature and contact of relay 156, conductor 88, terminal 32, brush 28, brush 17, terminal 20, magnet 3, arm 2, terminal 4, to the No. 1 commutator and ground. The switch indicated at 1 will operate identically as before to successively associate the No. 1, 5, 7, 3 and 2 commutators with this circuit. The relay 329, which, as shown, may be utilized to position a type wheel or other marking device, responds once for each impulse, and the magnet 330, which is slow-acting, will release at the end of each series of impulses and such release may be utilized to shift the switch indicated at 332 either for the purpose of associating the magnet 329 with another recording device, or the release of such magnet may be utilized as shown to bring the record strip in contact with the recording mechanism, and to feed the record strip another step. After five series of impulses, and hence after the number of the calling line has been recorded, the arm of the switch 332 is brought into association with the last contact and a circuit is established for magnet 330 which in turn closes a circuit for the release magnet 328, which circuit extends from battery, through the magnet 328, armature and front contact of magnet 330, contact of the switch 332 and arm thereof to ground. Relay 328 opens at its right-hand contact the previously traced circuit for the relay 325, which releases and opens a circuit to the calling line. When the relay 328 is energized, the magnet 330 deenergizes and moves the switch 332 into its normal position. The relay 328 is maintained energized over a ground at the back contact of the relay 339, but this circuit is only maintained for a short time, as the relay 339 is energized over a circuit through the left-hand armature

ture of relay 328 and opens the locking circuit for such relay. The operation of the relay 328 may be utilized as shown to control suitable apparatus for severing the record strip.

It will be apparent from the above description of the operation that the line identifying switch is operated twice if the connection is successfully established, and once if the connection is not successfully established, the first operation being utilized to control the indicating device to indicate to the operator the number of the calling line, and being operated the second time if the call is successful, and only if the call is successful, to make a record for the purpose of charging the call to the calling line. The first of these operations takes place entirely automatically without any act on the part of the operator, and the second in response to the operator's manipulation of the charge key.

What is claimed is:

1. In a telephone exchange system, a calling line, an operator's position, means whereby said line may be associated with said position, an indicating device at said position arranged to be operated in response to impulses, a recording device at said position arranged to be operated in response to impulses, an impulse producing device common to a number of lines, means individual to each line for automatically associating the common impulse producing device with the indicating device, and means operative after the operation of said indicating device for operating said last mentioned means to automatically associate the impulse producing device with said recording device.
2. In a telephone exchange system, a calling line, an operator's position, means whereby said line may be associated with said position, an indicating device and a call-recording device at such position, a control circuit, means individual to the line for impressing a train of impulses identifying the line on said control circuit, means for associating the indicating device with the control circuit whereby such indicating device may be operated to indicate the number of the calling line, a called line and means operative only in case the calling line is extended to the called line, for associating the call-recording device with the control circuit whereby such call-recording device may be operated to record a call on such calling line.
3. In a telephone exchange system, a calling line, an operator's position, means whereby said line may be associated with said position, a called line, means controlled at said position for extending said calling line to said called line, an indicating device at such position operated when said calling line is associated with said position for identifying the calling line, and a recording

device at such position operative when said calling line is extended to the called line for recording a call on such calling line.

4. In a telephone exchange system, a calling line, an operator's position, means whereby such line may be extended to such position, a call-recording device at such position, means at the position whereby such recording device may be associated with the calling line, means individual to the calling line for operating the recording device in accordance with the designation of the calling line, and means for preventing the association of such call-recording device with the calling line if the call is unsuccessful.

5. In a telephone exchange system, a calling line, an operator's position, means whereby such line may be extended to such position, a recording device at the position arranged to be operated in response to a train of impulses to record a number identified by such train of impulses, an impulse-producing device common to a plurality of lines comprising a plurality of interrupters each individual interrupter producing a different number of impulses, and a switch individual to the line for automatically associating certain of said interrupters with such recording device.

30 6. In a telephone exchange system, a calling line, an operator's position, means for extending said calling line to said position, an indicating device, and a call recording device at such position, a control circuit, means 35 individual to the calling line for impressing a train of impulses identifying the line on said control circuit, a called line, means operative when said calling line is extended to said operator's position for associating said

indicating device with said control circuit 40 for operating said device to indicate the number of the calling line, and means operative when said calling line is extended to said called line for associating said recording device with said control circuit for operating said recording device to record a call on said calling line.

7. In a telephone exchange system, a calling line, an operator's position, means whereby said line may be extended to said 50 position, a control circuit, a recording device at the position arranged to be operated in response to a train of impulses over said control circuit to record a number identified by such train of impulses, an impulse-producing device common to a plurality of lines comprising a plurality of interrupters, a switch individual to the calling line for automatically associating certain of said interrupters with said control circuit, and an 55 operating magnet for said switch in said control circuit.

8. In a telephone system, a calling line, an operator's position, means for extending said calling line to said position, an indicating device, and a call recording device at such position, means individual to the calling line for producing successive trains of impulses identifying said calling line, and means for successively associating said indicating and recording devices with said impulse producing means for indicating the number of the calling line and recording a call on said calling line.

In witness whereof I hereunto subscribe 75 my name this 2nd day of March, A. D. 1917.

SAMUEL B. WILLIAMS, JR.
